UNITED STATES PATENT OFFICE

GEORGE W. CARRIGAN, OF CLEBURNE, TEXAS

SUPERHEATER-UNIT-TESTING DEVICE

Application filed December 9, 1929. Serial No. 412,688.

My invention relates to a device more particularly adapted for testing the superheater units employed in locomotives and has for its object the provision of a device which may be easily and quickly applied to and as readily removed from the ends of superheater units for the purpose of testing same before installation; a device which will be positive in its testing operation.

10 I am aware that various devices are at present in use for superheater unit testing, but said devices are of such construction that much time is lost in their operation.

15 While my invention is especially intended for locomotive superheater unit testing, it is apparent that my improved device may be used in other connections and operations.

20 The objects and advantages of my invention will be readily comprehended from the detailed description of the accompanying drawings, wherein—

25 Figure 1 is a plan view, with portions in section, of my improved device and portions of the fluid or medium supply lines broken away.

Figure 2 is a side elevation of the device shown applied to the ends of a superheater unit of which intermediate portions are broken away.

30 Figure 3 is a detail sectional view taken substantially on the line 3—3 of Figure 1 looking in the direction of the arrows.

35 Figure 4 is a sectional and side elevation of my improved device shown applied to the ends of a superheater unit of which portions are broken away.

Figure 5 is a view taken substantially along the offset line 5—5 of Figure 1, as viewed by the arrows.

40 Figure 6 is a sectional view taken substantially on the line 6—6 of Figure 4, as viewed by the arrows.

45 In the particular exemplification of the invention as disclosed in the drawings, A illustrates a superheater unit, the intermediate portion whereof is broken away; the unit being provided with the two ends 10 and 11 and these ends provided with the usual super- 50 heater unit clamp 12 employed in the in-

stallation of the unit to hold the unit in place when in service on a locomotive.

The ends 10 and 11 of the superheater unit are usually provided with the enlarged portions 13 which are seated in the usual washers 14 for effecting fluid-tight connections when in service. The outer ends of the superheater units are provided with rounded enlargements or heads 15 for a "ground joint" connection with the superheater header not shown; the rounded heads being intended to receive a gasket 16 of leather or any other suitable material for effecting a water-tight joint with the tester now to be described.

55 My improved tester comprises a closed chamber 17 which is surrounded by a cylindrical piston 18, having a fluid-tight relation with the walls of the chamber 17 by means of a suitable packing 19 of proper form and suitable material and held in place by plate 20 shown bolted to the end wall of the chamber 17 by bolts 21. The end wall of the chamber 17, which is provided with the packing 19, is provided with a port 22 which permits fluid to flow from chamber 17 into the 60 closed end of the cylindrical piston 18.

65 The base portion of the chamber 17 is provided with ports 23 and 24; the port 23 receiving one end of a pipe 25, while the port 24 receives one end of a pipe 26; the two pipes 70 being shown threaded into the ends of the ports. The outer end of pipe 25 is connected to one outlet of a three-way valve 27; while the outer end of pipe 26 is provided with a discharge plug valve 28 having an operating 75 handle 29 for controlling outflow into discharge pipe 30 which may lead to a container or other suitable point of discharge.

80 One end of the three-way valve 27 has a connection 31 which, in turn, connects with a water supply line 32 which leads to a suitable source of fluid or water under pressure. The other end of three-way valve 27 is provided with a connection 33 having an air supply 85 conduit or pipe 34 connected thereto and leading from a suitable source of air under pressure.

85 The connection at the end of fluid pipe 32 is provided with a pipe 35 having a three-way valve 36 which has a pipe 37 whose oppo-

site end extends through a slot 38 formed in the side wall of cylinder-piston 18 and is connected in a hole in the wall of chamber 17 for admitting fluid into said chamber for the purpose of operating the piston 18, when the valve 36 is in the position shown in Figure 3.

The side wall of the cylindrical piston 18, on opposite sides, is provided with suitable brackets 39, 39, for the purpose of pivotally securing the anchors or clamp members 40, 40.

The upper ends of the anchors 40, 40 are shown preferably bowed inwardly toward each other and are formed with hand-grasping portions 41; while the lower or opposite ends are provided with inwardly disposed hook portions 42, which are adapted to engage beneath the usual superheater unit clamp member 12. The anchors 40, 40, intermediate of their pivotal points 43, 43 and the hook ends 42, 42, are shown provided with apertured lobes 44 to receive a suitable contracting spring 45, which normally draws the hook ends 42 into engagement with the under side of the unit clamp member 12, as shown in the drawings.

The three-way valve 36 is provided with a discharge outlet 46 which may connect with a line or pipe for conveying the fluid to any suitable source of storage or waste.

My improved tester is a portable device intended for testing large numbers of superheater units clustered on the shop floors or trucks for the purpose of determining whether the units are leak-proof before installation on locomotives; and in order that the tester may be moved it is, of course, necessary that the pipes 32 and 34 be provided with suitable flexible connections, such as hose, flexible conduits or joints.

In operation, it will be understood that pipe 32 is connected with some suitable fluid supply, preferably water under pressure; while pipe 34 is connected with a suitable supply of air under pressure; valve 27 it being understood should initially be closed.

The superheater unit clamp member 12 is arranged at the ends 10 and 11 of the superheater unit A, as shown in the drawings, and my improved testing device is then applied with the heads or enlarged portions of the superheater unit ends arranged in the sockets or enlarged orifices of the ports 23 and 24 in the base of the chamber 17, as shown in the drawings, with a suitable packing element or washer therebetween so as to provide a fluid-tight seating.

In order to hold the loosely mounted superheater unit clamp element 12 in proper position while applying my testing device, I prefer to employ the clamp member shown at 47 in Figures 1 and 4, which consists of a pair of handle members or bars 48, 48, pivotally connected together at 49 and having jaw portions 50 formed to encircle or fit about the round end of one of the superheater units,

as shown in Figure 4. The jaw portions 50 are held in gripping relation with the superheater unit end by means of a spring 51 (see Figure 1). With this clamp placed beneath the superheater clamp element 12, it is apparent that the latter will be held in place at the enlarged ends of the superheater unit A until the testing device has been put into place. This permits the operator to use both hands in applying and manipulating the testing device; the temporary clamp element 47 may be removed after the testing device has been applied to the superheater unit A.

The testing device is applied by grasping handles 41, 41 of the anchor member 40 and drawing the handles together so as to separate the jaw or hook ends 42 so as to enable these hook ends 42 to be placed about the superheater unit clamp element 12, with the hook ends engaging therebeneath, as shown in the drawings. Valve 36 is then opened to allow water,—or other suitable fluid—which is under a suitable pressure, to flow through pipe 37 and into chamber 17. The water is allowed to fill chamber 17 and to flow through port 22 into the piston 18. This will build up a pressure in cylindrical piston 18 and cause it to move upward.

As the anchor members 40, 40 are pivotally connected to the piston 18 by the brackets 39, the anchor will likewise move upward and thereby draw the enlarged ends of the superheater unit A firmly into the socketed or enlarged orifices of ports 23 and 24 in the bottom of the testing device and provide a water-tight seal.

Valve 27 is now set so that its ports will register with the water pressure pipe 32 and with pipe 25, thus allowing the water to pass through port 23 and into end 10 of the superheater unit A.

As soon as the superheater unit A is filled, the water—or other medium—will flow out of superheater unit end 11, through port 24, into pipe 26. Before opening valve 27, which is controlled by handle 27^a, it will be understood that valve 28 is opened. As soon as the water discharges through pipe 30, valve 28, operated by handle 29, is then closed, thus causing pressure to build up in the superheater unit equal to the pressure in supply line 32, thereby providing effectual testing means for leaks in the superheater unit.

When the test has been completed, valve 27 is then set so as to bring its ports into register with the connection from the compressed air supply line 34 and with pipe 25, while at the same time valve 28 is opened. The compressed air flowing through pipe 25, port 23 and into end 10 of the superheater unit A will force the water out of the superheater unit and through pipe 26 and discharge pipe 30.

The three-way valve 36, operated by handle

36^a, is then closed against inflow of the water from pipe 35 and connection 37 into the chamber 17; the valve 36 being set so as to allow the water to discharge through outlet 46, thereby relieving the pressure on piston 18 and hence release the clamped relation between the device and the superheater unit; permitting the anchor member 40 to be released and be applied to the next unit to be tested. The water coming from the cylinder may be conducted to some suitable container to prevent wasting if desired.

I have shown what I believe to be a desirable form of my invention, which I have described in terms employed merely as terms of description and not as terms of limitation, as structural modifications may be made without, however, departing from the spirit of my invention.

20 What I claim is:—

1. A device of the character described comprising ported means adapted to receive the orificed ends of a superheater unit; a pressure medium receiving conduit communicating with one port of said means; a discharge conduit communicating with the other port of said means; means, operable by a medium under pressure, whereby said ported means and the superheater unit are clamped together; and controllable means whereby a fluid under pressure and compressed air are alternately admitted to said pressure medium receiving conduit.

2. A device of the character described comprising a pressure medium receiving chamber; a piston operable by the medium entering said chamber; anchor elements pivotally carried by said piston; a pressure medium receiving member adapted to register with one end of a superheater unit; a discharge member adapted to register with the other end of the superheater unit; and means having communication with a pressure fluid supply and a compressed air supply and with said pressure medium receiving member whereby a pressure fluid and compressed air may alternately be admitted to said pressure medium receiving member.

3. A device of the character described comprising a member provided with a pair of fluid conveying channels having flared orifices to receive the headed ends of a superheater unit; a pressure fluid supply line and a compressed air line; means for selectively placing said lines in communication with one of said channels; a fluid receiving chamber; a piston reciprocably associated with said chamber; a pair of jaw members connected with said piston and adapted to engage with the superheater unit, whereby movement of the piston induced by admission of fluid to said chamber will draw the headed ends of the superheater unit into the orifices of said channels; and means for controlling outflow through the other of said channels.

4. A device of the character described comprising a chambered member provided with a base having a pair of ports; pipes secured to one of the ends of each of said ports; a cylindrical piston slidably surrounding said member in fluid-tight relation therewith; the upper end of said chambered member having a port whereby fluid is admitted into the piston; controllable means whereby a fluid and compressed air are alternately admitted to one of said pipes; a pair of superheater unit engaging members pivotally secured to said piston whereby upward movement of the piston will hold the superheater unit ends against the ports in said base; and controllable means for admitting fluid into the chambered member.

5. A device of the character described comprising a closed chamber provided with an outlet port in one end wall and a controllable inlet; a piston telescopically mounted over the outlet port end of said chamber in fluid-tight relation therewith; a pair of fluid conveying conduits secured to the opposite outer sides of the chamber; controllable means connected with one of said conduits whereby fluid under pressure and compressed air may alternately be admitted to said conduit; a pair of jaw members connected to opposite sides of said piston so as to move therewith; means for forcing the jaw ends of the jaw members toward each other, whereby the ends of a superheater unit are held in position beneath the ends of said conduits; and means for controlling the outflow from the other of said conduits.
